UNITED STATES PATENT OFFICE.

JOHN C. GOODRIDGE, JR., OF NEW YORK, N. Y.

CULVERT OR WATER-WAY.

SPECIFICATION forming part of Letters Patent No. 354,897, dated December 28, 1886.

Application filed May 8, 1886. Serial No. 201,528. (No model.)

To all whom it may concern:

Be it known that I, JOHN C. GOODRIDGE, Jr., of the city, county, and State of New York, have invented a new and useful Improvement 5 in the Construction of Culverts and Water-Ways, of which the following is a specification, reference being had to the accompanying drawings.

In times of freshet culverts and similar water-ways, when constructed in the usual manner, are apt to become obstructed by floating material washed down from the inundated country. The first obstruction which lodges in the water-way serves to check the passage 15 of other drift, thus constantly adding to the strength and imperviousness of the barrier. The water is dammed back and rises. Its pressure renders the removal of the obstruction difficult, if not impossible. Finally, if 20 relief is not found, the water cuts a new channel for itself, and soon sweeps away the whole or a great part of the structure the water-way was intended to preserve.

My invention consists in certain improvements in the construction, whereby a washout 25 is obviated, and wherein the water-way is always open and free for the escape of water, notwithstanding the greater or less lodgment of floating matter at its mouth.

30 In the drawings forming part of this specification, Figure 1 shows an elevation of my method of construction; Fig. 2, a perspective view of the same as applied to a railway-culvert of masonry. Fig. 3 is an elevation to 35 illustrate the manner in which my invention accomplishes its purpose, and Fig. 4 is a perspective view of a railway-culvert constructed of beton or artificial stone upon my method.

A represents the entrance of a culvert or 40 water-way. From each side of the culvert or water-way side walls, B, are built, projecting upstream to a distance approximately equal to twice the width of the water-way. These side walls, B, should be carried up to high- 45 water mark. The interval, C, between the side walls, B B, is paved with masonry or concrete, or planked, or protected in any other manner which will resist the action of flowing water. An invert of beton is preferred for this pur- 50 pose. Provision should also be made to prevent the undermining of the floor C. This may be done by the cross-walls D, or in any

other manner which local circumstances demand. The ends of the side walls, B B, should slope upward and toward the water-way, as 55 shown in the various figures, and I prefer to unite the side walls, B B, to the face of the water-way by an incline, as shown in Fig. 4. While neither of these particular features are absolutely essential elements of my invention, 60 they add to its efficiency.

In brief, my invention consists in adding to a culvert or water-way a passage projecting upstream in the nature of a flume, the top of which is open, and the depth of which equals 65 the depth at high water, while its width is the same as that of the culvert or water-way, and its length is double the width of the culvert or water-way.

I do not intend to limit myself to the precise height or length of the side walls, B B, above set forth. The dimensions given are a good general rule, applicable to the great majority of cases. Local circumstances and conditions may demand modifications. For instance, the amount of water to be discharged by the water-way varies greatly at different times, and where the amount of floating matter is unusually large at periods of high water it will be well to lengthen the side walls, B B, 70 to more than twice the width of the water-way. Again, the object of the cross-walls D D and the floor C is to prevent undermining. Other means and methods may better accomplish this purpose in some peculiar cases. 75

Upon referring to Fig. 3, the way in which my method of construction accomplishes its purpose will be apparent. Floating matter is borne by the rising water downward until the side walls, B B, are encountered. Unless long 80 enough to bridge the opening between those walls, it passes through the flume and water-way. At last something lodges upon the ends of those walls, collects other floating matter, and a dam is formed barring in whole or in 85 part the passage between the ends of the walls. The water rises, flows over the obstruction like a dam, (see E, Fig. 3,) finds a ready escape between E and F, and passes through the culvert or water-way in undiminished volume. 90 Should the buoyancy of the material, the force of the current, and the inclined ends of the side walls, B B, cause the obstructions to rise 95 and roll along the top of those walls, they can-

not lodge in any event before the point F is reached, while if they do not roll evenly over the top of those walls while in transit to F, and they usually will not, they will be so turned 5 as to admit of their being carried through the culvert or water-way and downstream. Thus the space between E and F is always open to the water, and the side walls, B B, should be made long enough to insure an ample free 10 space for this purpose, even after all probable accumulation at F. Should the side walls, B B, be joined to the culvert or water-way by an incline, as shown in Figs. 3 and 4, which is the construction I prefer, floating matter ac- 15 cumulating at F will be forced to a very considerable extent up that incline, thus tending to keep the passage between E and F clear and unobstructed.

Having thus described my invention, what I 20 claim as new, and desire to patent, is—

1. A culvert or water-way constructed with an upstream flume or extension, the depth of which is less than the height of said culvert or water-way, substantially as specified.

2. A culvert or water-way constructed with 25 an upstream flume or extension, with an intermediate inclined abutment leading from the sides of the extension to the top of the culvert, substantially as and for the purpose specified.

In testimony that I claim the foregoing improvement in the method of constructing culverts and water-ways, as above described, I have hereunto set my hand this 30th day of April, 1886.

JOHN C. GOODRIDGE, JR.
